UNITED STATES PATENT OFFICE.

WILLIAM P. COLLINS, OF BOSTON, MASSACHUSETTS.

ROTARY BRAKE MECHANISM.

1,102,325.

Specification of Letters Patent.

Patented July 7, 1914.

Application filed March 17, 1913. Serial No. 754,695.

To all whom it may concern:

Be it known that I, WILLIAM P. COLLINS, a citizen of the United States, residing at Boston, in the county of Suffolk and State of Massachusetts, have invented new and useful Improvements in Rotary Brake Mechanisms, of which the following is a specification.

This invention relates to rotary brake mechanisms, the object being to provide a brake comprising a piston carrier provided with one or more pistons and a casing within which said carrier is arranged. The casing is provided with a chamber arranged outside of and adjacent to a portion of the periphery of said carrier and as either the casing or said carrier, preferably the latter, is rotated relatively to the other, said pistons are adapted to be moved from a position inside of the periphery of said carrier to project laterally therefrom as said pistons are passing through said chamber to cause the air or liquid contained in said chamber to be compressed or forced from one side of said piston to the other, and thereby retard or check the movement of one of said members relatively to the other.

The object is further to provide means adapted to cause said pistons to project laterally from said carrier within the confines of said chamber to a greater or less predetermined degree.

The invention consists in the combination and arrangement of parts whereby the above objects and certain other objects hereinafter appearing are attained, as set forth in the following specification and particularly pointed out in the claims.

Referring to the drawings: Figure 1 is a transverse section through a brake mechanism embodying my invention. Fig. 2 is a section partly in elevation taken on line 2-2 of Fig. 1 as viewed in the direction of the arrows on said line, parts of said mechanism being broken away to save space.

Like numerals refer to like parts throughout both views of the drawings.

In the drawings, 4 is a piston carrier, preferably cylindrical in shape, and 5 is a casing within which said piston carrier is mounted upon a shaft 6 which is journaled in suitable bearings 7 arranged at opposite ends of the casing 4. A portion of the inner wall of the casing 5 is arranged concentric with the carrier 4 and is adapted to substantially engage the periphery 8 of said

carrier. This portion preferably extends from a point "a" in the direction of the arrow "b", Fig. 1, to the point "c" substantially diametrically opposite said point "a". The remaining portion of the casing 5 is offset or in other words the inner wall 9 thereof is eccentrically arranged relatively to the carrier 4 and forms a crescent shaped chamber 10 between the periphery 8 of the carrier 4 and the wall 9.

The chamber 10 is filled with a suitable fluid preferably oil and as either said casing or said carrier, preferably the latter, is rotated relatively to the other more or less of the oil contained within said chamber will be carried around therewith and lubricate the same permitting said carrier to be rotated freely and without resistance. The carrier 4 is provided with one or more pistons 11 which are preferably slidably arranged in radially disposed slots 12 and are carried around with said carrier during the rotation thereof.

The pistons 11 during the normal operation of the device are retained in the positions illustrated in Fig. 1, that is with their outer ends either within or substantially aligning with the periphery 8 and therefore creating no resistance against said carrier 4, said pistons being yieldingly retained in such positions preferably by springs 13, which are inserted through slots 14 in said pistons and engage the inner wall 15 of the piston carrier 4. When it is desired to check the relative movement between the carrier 4 and the casing 5 said pistons are moved radially relatively to said carrier in said slots 12 to project laterally from said carrier 4 beyond the periphery 8 to a predetermined variable degree during the passage of said pistons through the chamber 10, said degree of projection being governed by the speed of the moving parts and as to whether it is desired to entirely check the rotations thereof or merely retard the same. Means are provided for moving said pistons radially relatively to said carrier 4, said means preferably consisting of an expansible cylindrical member 16 which is arranged within said casing 5 and within the recess 17 formed in said carrier 4, substantially concentric with said carrier. Said cylindrical member 16 comprises two parts 18 and 19, the part 18 is preferably a stationary member and is secured to the casing 5, while the member 19 is arranged to slide on said mem-

ber 18 and to be guided thereon by members 20 which extend longitudinally of said cylindrical member.

Many means may be employed for expanding and contracting the cylindrical member 16, or in other words, to move the member 19 relatively to the member 18, but as a convenient and inexpensive expedient, I have provided a collar 21 loosely mounted 10 upon the shaft 6 and abutting against the ends of the hub 22 of the carrier 4, said collar having pivoted thereto at 23 one end of a toggle 24. The toggle 24 is pivotally connected at the middle thereof by a pin 25 15 to the member 19, while the other end of the toggle 24 is connected at 26 to a sleeve 27 arranged to slide longitudinally of the shaft 6, said sleeve being arranged in non-rotatable relation to the end wall 28 adjacent thereto. The portion of said sleeve 20 which projects through said end wall is 25 preferably square and extends somewhat beyond said end wall and constitutes a bearing for the shaft 6. A flange 29 is formed 30 upon said sleeve upon either end thereof within said casing and is adapted to engage the inner wall of the end plate 28 to limit the movement of said sleeve toward said casing. It is essential that means be provided to normally retain said expandible member 35 16 contracted and for this purpose a spring 30 is provided which is coiled about the shaft 6, engaging at one end thereof of the collar 21, while the opposite end of 40 said spring projects into a recess 31 at the inner end of the sleeve 27 and is seated against said sleeve, thereby yieldingly forcing said collar 21 and said sleeve 27 apart and straightening or tending to straighten 45 the toggle 24, the result being to yieldingly retain said cylindrical member in its contracted relation to said carrier.

In the foregoing description, mention has been made of but one expandible member, 45 but in Fig. 2 I have illustrated a pair of expandible cylindrical members arranged adjacent opposite ends of the casing 5, said expandible members being identical in construction and each contained in a recess 17, 50 one of said recesses being formed in each end of the rotary member 4. This arrangement provides a more uniform adjustment or operating means for the pistons 11 provided they are operated simultaneously, and 55 as a preferred means for simultaneously operating said toggles 24 and from the exterior of the casing 5, I have provided a lever 32 pivoted at 33 to the casing 5, said lever being pivotally connected at 34 to the 60 outer end of the sleeve 27 toward the left-hand end of the casing 5. The outer free end of the lever 32 is provided with a handle 35 by which said lever may be rocked to reciprocate said sleeve 27 longitudinally of 65 the shaft 6. The sleeve 27 at the opposite

end of the casing 5 is connected to the lever 36 pivoted at 37 to said casing and upon the opposite side of the shaft 6 from the pivot 33 of the lever 32. The free end of the lever 36 extends upwardly beyond the 70 edge of said casing and is connected by a link 38 to the free end of the lever 32 adjacent to the handle thereof, consequently as said lever 32 is rocked in the direction of the arrow "d" the sleeve 27 at the left 75 of said casing will be reciprocated longitudinally of the shaft 6 inwardly. Said movement of the lever 32 also causes the lever 36 to be rocked in the direction of the arrow "e" and consequently the sleeve 27, 80 at the right-hand side of the casing 5, will also be reciprocated longitudinally toward the interior of said casing and thereby simultaneously move the pivots 23 and 26 of the toggles 24 toward each other, collapsing 85 said toggle and causing the movable members 19 to be moved from a position in which the periphery of the member 19 is concentric with the axis of the rotary member 4 into a position eccentric thereto or to a position concentric with the 90 inner wall 9 of the crescent shaped chamber 10, as illustrated in dotted lines Fig. 1, said movable member 19 being 95 guided by the members 20 upon the stationary portion 18. The two positions mentioned relative to the member 19 are the positions in which the periphery of the member 19 is concentric with either the periphery of the rotary member or with the 100 wall 9, the positions being the extreme positions thereof, but it is not always necessary for said member 19 to be moved this entire distance, but may be moved to predetermined portions thereof for the purpose 105 hereinafter set forth.

In the operation of the device either the carrier 4 or the casing 5 may be rotated relatively to the other member, but preferably the carrier is the rotatable member, as hereinbefore stated, this being the normal operating condition of the device. When it is desired to check the rotary movement of said carrier the lever 32 is rocked upon its pivot to cause the sleeves 27 to move lengthwise of the shaft 6 toward the interior of the casing and by this movement the movable member 19 will be moved toward the position indicated in dotted lines, Fig. 1, a predetermined amount or according to the 110 checking power desired. By the movement of the member 19, the pistons 11 as they are revolved with the carrier 4 in the direction of the arrow "b" engage the periphery of 115 said member 19 and are forced outwardly to project to a greater or less degree beyond the periphery 8 of the carrier 4 as they pass through the chamber 10 and thereby engage the oil, or any other suitable fluid, 120 contained within said chamber. Said oil 125 130

or other fluid will be carried forward by the projecting portion of said blade and compressed owing to the configuration of the chamber 10, or if said blade is projecting but slightly beyond said periphery the oil in advance thereof will escape to the rear of said blade with a consequent retardation of said rotary member or a sudden checking thereof according to the degree to which said piston is projected.

In the drawings the oil is shown filling the chamber 10 and this is the preferred arrangement, it may be desirable however to completely fill the recesses 17 with oil in order to insure the chamber 10 being always completely filled.

From the foregoing description it will be seen that simple and efficient means are provided for accomplishing the objects of the invention, but while the elements herein shown and described are well adapted to perform the functions set forth, it is obvious that various minor changes may be made in the proportions, shape and arrangement of the several parts, without departing from the spirit and scope of the invention as defined in the appended claims.

Having thus described my invention what I claim and desire by Letters Patent to secure is:

1. A brake mechanism having, in combination, a casing, a piston carrier, one of said members rotatable relatively to the other, said casing having a crescent shaped chamber formed outside of and adjacent to the periphery of said carrier, a shaft to which said carrier is secured, said shaft being journaled in said casing, a series of pistons carried by said carrier, means to normally retain said pistons with their outer ends flush with the periphery of said carrier, and means to move said pistons to project laterally from said carrier a predetermined distance into said chamber, said means including a toggle.

2. A brake mechanism having, in combination, a casing, a piston carrier, one of said members rotatable relatively to the other,

said casing having a crescent shaped chamber formed outside of and adjacent to the periphery of said carrier, a shaft to which said carrier is secured, said shaft being journaled in said casing, a series of pistons carried by said carrier, means to normally retain said pistons with their outer ends flush within the periphery of said carrier, an expansible cylindrical member arranged within said casing substantially concentric with the axis of said carrier, a collar loosely mounted on said shaft, a sleeve slidable longitudinally on said shaft, a spring interposed between said collar and said sleeve to yieldingly separate the same, a toggle pivotally connected at one of its ends to said collar, said toggle being pivoted at its opposite end to said sleeve and at its middle to one portion of said expansible member, and means to reciprocate said sleeve on said shaft to collapse said toggle whereby said cylindrical member will be expanded.

3. In a brake mechanism a casing, a piston carrier arranged to rotate within said casing, said casing having a chamber formed therein at one side of and adjacent to the periphery of said carrier, a series of pistons carried by said carrier and movable radially relatively thereto, springs adjacent opposite inner ends of said pistons adapted to normally retain said pistons within the periphery of said carrier, expansible cylindrical members arranged within the opposite ends of said carrier, means to yieldingly retain said cylindrical members contracted, and means adapted to simultaneously expand said cylindrical members to engage said pistons at opposite ends thereof and move the same outwardly in said carrier during the rotary movements of said carrier.

In testimony whereof I have hereunto set my hand in presence of two subscribing witnesses.

WILLIAM P. COLLINS.
